(57) **CLAIM**

The ornamental design for a clamp for fixing decking boards, as shown and described.

DESCRIPTION

FIG. 1 is a front, left, and bottom perspective view of the clamp for fixing decking boards showing the new design; FIG. 2 is a front, left, and top perspective view thereof; FIG. 3 is a front elevation view thereof, the rear elevation view being a mirrored image thereof; FIG. 4 is a top plan view thereof; FIG. 5 is a bottom view thereof; FIG. 6 is a left side elevation view thereof; and, FIG. 7 is a right side elevation view thereof.

1 Claim, 6 Drawing Sheets
